UNITED STATES PATENT OFFICE.

ARTHUR G. GLASGOW, OF RICHMOND, VIRGINIA, ASSIGNOR TO THE UNITED GAS IMPROVEMENT COMPANY, OF PHILADELPHIA, PENNSYLVANIA, A CORPORATION OF PENNSYLVANIA.

APPARATUS FOR THE MANUFACTURE OF WATER-GAS.

1,115,065.

Specification of Letters Patent.

Patented Oct. 27, 1914.

Application filed November 11, 1911. Serial No. 659,751.

To all whom it may concern:

Be it known that I, ARTHUR G. GLASGOW, a citizen of the United States of America, residing in Richmond, county of Henrico, 5 and State of Virginia, but temporarily an inhabitant of the city of Westminster, county of London, England, have invented certain new and useful Improvements in Apparatus for the Manufacture of Water- 10 Gas, of which the following is a true and exact description; reference being had to the accompanying drawings, which form a part thereof.

My invention relates to the manufacture 15 of water gas by the intermittent process where the run or period of gas-making (when heat is absorbed from the fuel-bed) and the blow or period of air blasting (when heat is restored to the fuel-bed) alternate. 20 In this process there is now usually employed a generator through which the air-blast passes always upward, whereas the direction of the gas-making steam is reversible so that it passes either upward or down- 25 ward at the option of the operator. But, where economy in fuel is of prime importance and it is desired to minimize the percentage of CO in the generator blast products, the twin-generator system has been 30 adopted. This system alters the distribution of the fuel-bed during gas-making from that provided during air-blasting, by connecting two generators at the bottom so that the air blast always passes upward 35 through them in parallel, whereas the gas making steam passes down through one and up through the other, in alternating series. Therefore, more complete conversion of the oxygen of the steam to CO is insured by the 40 passage of the steam through two heated fuel beds, whereas the divided air blast passes through but one fuel bed; thus minimizing the percentage of CO₂ in the water gas and the percentage of CO in the 45 blast products. The objection to this twin generator system is that the output of gas is but little more than half of that obtained from a single generator of the same grate area. To overcome this deficiency, I have 50 increased the depth of each of the twin generators to that of my single generators, and in addition to or in substitution for

series steaming, I have admitted steam in carefully regulated and varying proportions to the bottoms of the twin generators; but even when so much bottom steam is substituted for series steam (either in modified series running or for parallel uprunning) that it seriously disturbs the proper distribution of heat, causing the clinker to adhere to the generator wall and notably reducing the efficiency of the system, the output from a modern single generator still remains nearly one third greater than that obtainable with the twin generator system. This has hitherto been considered an inherent disadvantage, inseparable from the twin generator system, which must be compensated for by superior fuel economy, and special efforts have been made to minimize this disadvantage in carbureted water gas construction by the use of common fixing chambers, blast valves, etc., and otherwise simplifying and perfecting twin generator plant. Now I have ascertained that if the gas making steam could be passed downward in the two generators simultaneously instead of through both generators serially, a great increase in output of gas would result, and I have invented a plant comprising two generators connected as by a common bottom through which generators the gas making steam in proper proportions passes simultaneously either all downward or all upward, or serially in either direction supplemented by steam for the second generator if and as desired, at the option of the operator. Conveniently, each generator has top and bottom steam inlets, top and bottom gas outlets, and air blast inlets, the bottom gas outlets remaining closed when steam is admitted to the top of one generator or to the top of the other generator or to the bottom of both generators, but opening when the top gas outlets are both closed and steam is admitted simultaneously to the tops of both generators; thus, when the other inlets and outlets are correspondingly opened and closed, converting the plant into what is, in effect, either two generators working together as a pair of generators according to the single generator system, or a single setting of twin-generator plant. By this invention, I am therefore enabled to work ac-

5 cording to either of two processes with a single plant; the one method possessing all of the advantages as to capacity of the single generator system, where the gas-making steam passes either all upward or all downward, with the further advantages, in the larger sizes, that the former single generator is divided into a pair of smaller generators, thus facilitating clinkering and the more perfect distribution of air and steam throughout the cross-sections of the smaller fuel-beds; and the other method having all of the economical and structural advantages of the modern twin-generator 10 system, where the gas making steam passes for a time all upward through the two generators in parallel and then for a time down through one generator and up through the other generator in alternating series, supplemented by steam for the second generator if and as desired, at the option of the operator; or vice versa.

15 The chief difficulty in supplying gas is to adjust the production to the demand without waste and extra investment in reserve and storage plant, but with my invention an increase in output of nearly one-third is immediately available at will without the labor, waste of fuel, wear and tear 20 and delay incidental to starting up a spare section. Thus, three sections of plant while working normally at maximum twin-generator efficiency, can be immediately changed to the single generator system of working 25 so as to produce for any length of time the approximate output of four such sections working on the twin generator system, without increase in the cost of generating labor and repairs, and without the necessity 30 of keeping plant and specially-trained men in reserve for occasional use. This optional increase in capacity is, therefore, worth far more than its equivalent in additional new plant, while, on the other hand, the cost of 35 this additional capacity is far less than new plant.

40 The apparatus can be variously arranged, but it is preferable that the valve mechanism be such that it can be set, as by the movement of a clutch, to insure the proper operation of the various controlling devices when running on the one system or the other until re-set. Furthermore, it is preferable that, in changing over from the one system to the other, the proportional distribution 45 of steam to the generators should be automatically varied to suit the different conditions.

46 The various features of novelty which characterize my invention are pointed out with particularity in the claims annexed to and forming a part of this specification. For a better understanding of the invention, however, and the advantages possessed by 51 it, reference should be had to the accom-

panying drawings and descriptive matter in which I have illustrated and described one form in which my invention may be embodied.

52 Of the drawings, Figure 1 is a plan thereof with some portions removed; Fig. 2 is a side elevation, partly in section, with the near generator removed. Fig. 3 is a front elevation, partly in section, with some portions removed. Fig. 4 is a detail view showing the valve setting mechanism in its operative position for steaming in parallel in either direction.

53 In this arrangement, the bottoms of the generators a' and a'' are connected together by the conduit c' which has an optional gas outlet passage o'' controlled by the valve v'' , and the tops of the respective generators are provided with blast and gas outlet passages o' and o'' controlled by the valves v' and v'' operated by the levers f' and f'' . These levers f' and f'' are also operatively connected as by arms t^{10} and links t^{11} with the shafts t' and t'' respectively. These shafts are in line with each other and are 58 adapted to be coupled together and to the yoke y which is operatively connected by the link y' with the valve v'' .

59 f is a change lever operatively connected as by a link to the connecting link k^7 of the clutch k whose members k^4 , k^5 and k^6 are splined on the shafts t' and t'' , k^4 on shaft t' and k^6 and k^5 on shaft t'' , and coupled as by swivels as shown to the connecting link k^7 so that these members travel along the 64 shafts in response to the movement of the lever f . The said members k^4 , k^5 and k^6 are adapted to couple simultaneously these shafts with the yoke y at k' and k'' and with each other at k^7 (see Fig. 4) so that 69 the three valves v' , v'' and v^3 must all work together in unison, v^3 being closed when v' and v'' are both open and open when v' and v'' are both closed; but when the clutch is 74 not so engaged each shaft is free to rotate 79 separately without disturbing the yoke y or each other. When the valves v' and v'' are operated by hydraulic or other power so that the actuating power can be applied to both v' and v'' jointly, the clutch k need 84 only couple one of these valves v' or v'' with the yoke y .

85 b' is the valve, operated by the gearing g and wheel w , which controls the admission of air-blast to the bottoms of the two generators for blasting upward in parallel, and the blast-products issuing from the generators may be discharged into the atmosphere, or utilized for the production of steam, or passed into an oil-gasifying chamber c through the passages o' and o'' , as shown in the drawings, or disposed of in other ways. A separate blast valve may be used for each generator, if desired.

86 s is the steam cock controlling the ad-

mission of gas-making steam to the distributing and regulating system, which system automatically causes the steam to pass through the generators in proper proportion 5 all upward in parallel, or serially (down through one and up through the other) in either direction supplemented by whatever bottom steam (if any) may be desired, or all downward in parallel according to the 10 setting of the gas outlet valves.

s' , s^2 , s^3 , s^4 , s^5 , s^6 , s^7 and s^8 are the steam distributing cocks and p , p' , p^2 , p^3 and p^4 are the steam distributing conduits.

s' , s^2 , s^3 and s^7 are all operatively connected with the shaft t' to operate simultaneously with the valve v' , and in such manner that the valves s' and s^6 are closed and valves s^3 and s^7 are open when the valve v' is open or vice versa. The connection between the valves s' , s^2 , s^5 , s^7 and the shaft t' , comprises in the form shown an arm t^{12} secured to the shaft t' , a link t^{13} connecting the arm t^{12} to the operating arm s^{10} of the valve s' , a link t^{14} connecting the arm s^{10} to the 25 arm s^{11} secured to the elongated spindle s^{70} of the valve s^7 . The spindle s^{70} of the valve s^7 also has secured to it an arm s^{72} which is connected by a link s^{73} to the operating arms s^{30} and s^{50} of the valves s^3 and s^5 , respectively. The valves s^2 , s^4 , s^6 and s^8 are similarly connected with the shaft t^2 so that s^2 and s^4 are closed and s^6 and s^8 are open when v^2 is open or vice versa. In the connections between the valves s^2 , s^4 , s^6 and s^8 and the 35 shaft t^2 the parts t^{120} , t^{130} , t^{140} , s^{20} , s^{80} , s^{81} , s^{82} , s^{83} , s^{40} and s^{60} correspond to the parts t^{12} , t^{13} , t^{14} , s^{10} , s^{70} , s^{71} , s^{72} , s^{73} , s^{30} and s^{50} , respectively. The conduit p^3 is formed with a dual connection to the steam supply pipe and the valves 40 s^3 and s^4 are on one branch of the connection and the valves s^5 and s^6 are on the other branch of that connection, as will be seen from Fig. 2.

r , r' and r^2 with their respective steam meters m , m' and m^2 are means for regulating the steam when it passes through the generators in parallel; r being for the steam entering the connecting conduit c' and passing upward in parallel, and r' and r^2 being 45 for the simultaneous top supplies of steam which pass downward in parallel.

When steaming serially, the quantity of steam needed for the top of the first generator is more than that required for one generator but less than that required for both generators in parallel down-steaming; the proper intermediate regulation is provided by means of the regulating cock r^4 in the bypass connection p^4 , which is neutral in parallel down-steaming, but in series steaming automatically adds to the top of either generator any desired proportion of the total quantity of steam that is available for the top of the other generator in parallel down-steaming. Supplemental bottom steam in

series working is supplied, if and as desired, through the stop and regulating cock r^3 and the meter m^3 in the conduit p^3 . The several steam supplies are thus provided with separate independent regulation, so that the setting of any may be varied without altering the others.

As shown in Figs. 1, 2 and 3 of the drawings the change lever f is set to disengage the clutch k and the plant is ready for 5 steaming upward in parallel, or serially in either direction with optional bottom steam, according to whether both the valves v' v^2 are opened or only one of them; the valve v^3 is closed during the steaming upward in parallel or serially in either direction. For steaming upward in parallel both gas valves v' and v^2 are open, and consequently the steam cocks s^7 and s^8 (and s^3 and s^6) are open and s' , s^2 , s^4 and s^8 are shut; steam admitted through s passes through the regulating cock r , the cocks s^7 and s^8 , the conduit p controlled by them and meter m , into the conduit c' , and upward through the two generators in parallel, and the gas produced 90 leaves through the open passages o' and o^2 . Separate bottom steam connection and regulation may be used for each generator if desired instead of the single combination connection just described. For steaming serially in either direction as for example downward through the generator a' and upward through generator a^2 , the gas valve v' is closed by movement of the lever f' which also closes the steam cock s^7 (and the cock s^3) 95 thereby closing the steam conduit p to the bottoms of both generators and opens the steam cocks s' and s^6 thereby opening the steam inlet to the top of generator a' through the cock s' , the conduit p' and meter m' (s^2 100 being closed when the valve v^2 is open), so that the proper quantity of steam is automatically admitted through the regulating cocks r' and r^4 . Supplemental bottom steam, if and as desired, is admitted through the 105 stop and regulating cock r^2 and passes through the cocks s^5 and s^6 (s^3 and s^4 being closed), the conduit p^5 and the meter m^3 into the conduit c' and up through generator a^2 , the finished gases leaving this second generator by way of the open passage o^2 . To reverse the direction of serial steaming the gas valve v' is opened, thereby closing the steam cocks s' and s^6 and opening s^3 and s^7 , and the 110 gas valve v^2 is closed, thereby opening the steam cocks s^2 and s^4 and closing s^6 and s^8 ; the steam inlet to the top of generator a' is thus closed by the cock s' and that to the top of generator a^2 opened through the 115 cock s^2 , and the proper quantity of steam now automatically passes through the regulating cocks r^2 and r^4 , conduit p^2 and meter m^2 into the top of generator a^2 . The supplemental bottom steam, if any is admitted as 120 before at r^3 and now passes through the 125

5 cocks s^3 and s^4 (s^5 and s^6 being closed) the conduit p^s and the meter m^s into the conduit c' and up through generator a' , the finished gases now leaving by way of the open passage o' . A series run in either direction is 10 terminated by simply opening the shut gas valve v^2 or v' , and regulated steam is thereby automatically directed to the bottom of both generators for steaming upward in parallel as described above. Here again it is 15 obvious that separate supplemental bottom steam connection and regulation may be employed for each generator if desired instead of the single connection shown in the drawings.

To change from the alternating series method of twin-generator operation into a pair of generators which steam together in parallel either upward or downward, the 20 operator has only to move the change lever f to its other position as shown dotted in Fig. 3. This movement causes the clutch k to couple the shafts t' and t^2 with the yoke y at k' and k^2 and with each other at k^3 , 25 so that the two gas valves v' and v^2 and the optional gas outlet valve v^3 must all work together in unison, v^3 being closed when v' and v^2 are both open, and open when v' and v^2 are both closed. Steaming upward in 30 parallel now proceeds as already described, but upon moving either lever f' or f^2 to its other position as shown dotted in Fig. 3, both gas valves v' and v^2 are closed, and the gas valve v^3 opened. This movement 35 also causes the steam cocks s' and s^5 and s^2 and s^4 to open and s^3 and s^6 and s^8 to close thereby automatically directing properly regulated quantities of steam simultaneously to both generator tops for steaming downward in parallel; the supply to 40 generator a' being regulated and measured by the devices r' and m' , and the supply to generator a^2 by the devices r^2 and m^2 , the connection p^4 remaining neutral. The finished gases leave the generator bottoms by 45 way of the conduit c' and the passage c^3 through gas outlet valve v^3 ; or if desired a separate bottom gas outlet passage and valve may be provided for each generator. 50 The reversal of the steaming from downward in parallel to upward in parallel independently regulated is automatically effected by simply returning one of the levers f' or f^2 to its former position thereby causing both 55 gas valves v' and v^2 to open and the gas valve v^3 to close, which movement simultaneously closes the steam cocks s' and s^5 and s^2 and s^4 and opens s^3 and s^6 and s^8 thus closing both top steam inlets p' and p^2 60 and opening the steam inlet p to the bottom of both generators. To resume serial steaming, the change lever f is returned to its former position, thereby uncoupling the shafts t' and t^2 from the yoke y and from 65 each other.

The optional gas outlet valve v^3 , as shown, resists the normal working pressures by the weight of its disk, and the latter is adapted to lift when the pressure on its under side exceeds a predetermined amount 70 and this valve may be relied upon to automatically relieve the excess pressure within the generators should the three gas outlets become closed at the same time.

While in accordance with the provisions 75 of the statutes I have illustrated and described the best form of my invention now known to me it will be apparent to those skilled in the art that changes may be made in the form of the apparatus disclosed without departing from the spirit of my invention, and that certain features of the invention may be employed with advantage without a corresponding use of other features.

Having now described my invention what I claim as new and desire to secure by Letters Patent, is:

1. In apparatus for the manufacture of water gas, the combination of two generators each connected at one end to the other, and operating provisions including regulable means for withdrawing gas from, and supplying steam to, each end of each generator whereby, while the flow through the 90 generators may be in parallel in the blasting operation, in the gas making operation, the flow through the generators may be in series for the economical utilization of fuel in normal operation, or may be in parallel 100 when a greater generation of gas is required.

2. In apparatus for the manufacture of water gas, the combination of two generators each connected at one end to the other, 105 and operating provisions including regulable means for withdrawing gas from, and supplying steam to, each end of each generator whereby, while the flow through the generators may be parallel in the blasting operation, in the gas making operation the flow through each generator may be in either direction and may either be in series through the two generators for the economical utilization of fuel in normal operation, or be in parallel when a greater generation of gas is required.

3. In apparatus for the manufacture of water gas, the combination of two generators each connected at one end to the other, and operating provisions including regulable means for withdrawing gas from, and supplying steam to, each end of each generator whereby, while the flow through the generators may be in parallel in the 120 blasting operation, in the gas making operation, the flow through the generators may be in series and may be supplemented by steam supplied to the generator through which the gas flows last for the economical 125 130

utilization of fuel in normal operation, or may be in parallel when a greater generation of gas is required.

4. Apparatus for the manufacture of water gas comprising in combination two generators each connected at one end to the other and having an individual valve gas outlet from, and an individual valved steam supply connection to its opposite end, said generators also having a valved gas outlet from, and a valved steam supply connection to their connected ends.

5. Apparatus for the manufacture of water gas comprising in combination two generators each connected at one end to the other and having an individual gas outlet from and an individual valved steam supply connection to its opposite end, said generators also having a gas outlet from, and a valved steam supply connection to their connected ends, valves controlling said gas outlets, provisions, adapted to be brought into and out of operation at will, for connecting said valves so that the gas outlet at the connected ends of the generators will close and open as the other gas outlets open and close.

6. Apparatus for the manufacture of water gas comprising in combination two generators each connected at one end to the other and having an individual valved gas outlet from, and an individual steam supply connection to its opposite end, said generators also having a valved gas outlet from and a steam supply connection to their connected ends, valves controlling said steam supply connections and provisions connecting said valves so that the steam supply connection to the connected ends of the generators will close and open as the other steam supply connections open and close.

7. Apparatus for the manufacture of water gas comprising in combination two generators each connected at one end to the other and having an individual gas outlet from, and an individual steam supply connection to its opposite end, and a gas outlet from, and a steam supply connection to the connected ends of the generators, valves controlling said gas outlets and said steam supply connections and provisions adapted to be brought into or out of operation at will for connecting said valves so that the steam supply connection to each generator end will close and open as the gas outlet from that generator end opens and closes.

8. Apparatus for the manufacture of water gas comprising in combination two generators each connected at one end to the other and having an individual gas outlet from, and an individual steam supply connection to its opposite end, and a gas outlet leading away from, and a steam supply connection to the connected ends of the generators, valves controlling said gas outlets

and said steam supply connections and provisions adapted to be brought into or out of operation at will for connecting said valves so that the gas outlet at the connected ends of the generators will close and open as the other gas outlets open and close, and the steam supply connection to each generator end will close and open as the gas outlet from that generator end opens and closes.

9. Apparatus for the manufacture of water gas comprising in combination, two generators each connected at one end to the other and each having an individual valved gas outlet from, and an individual steam supply connection to its opposite end, and individual controlling valves for each of said steam supply connections, a valved gas outlet from and a steam supply connection to the connected ends of the generators, two valves, each controlling the last mentioned steam supply connection, and means so connecting one of the last mentioned valves with one, and the other with the second of said individual controlling valves, that the last mentioned steam supply connection will be opened when and only when both said individual steam connections are closed.

10. Apparatus for the manufacture of water gas comprising in combination, two generators each connected at one end to the other and each having an individual gas outlet from, and an individual steam supply connection to its opposite end, individual valves controlling said outlets and connections, a valved gas outlet from and a steam supply connection to the connected ends of the generators, two valves, each controlling the last mentioned steam supply connection, inter connections between one of the last mentioned valves and the valves controlling the gas outlet from and steam supply connection to one of said opposite generator ends and interconnections between the remaining valves specified, all so arranged that the steam supply connection to the connected ends of the generators is opened when and only when the other steam supply connections specified are closed and the steam supply connection to said opposite end of each generator opens and closes as the corresponding gas outlet closes and opens.

11. Apparatus for the manufacture of water gas comprising in combination, two generators each connected at one end to the other, and each having an individual gas outlet from, and an individual steam supply connection to its opposite end, valves controlling said gas outlets and steam connections, a gas outlet from and a steam supply connection to the connected ends of the generators, two valves, each controlling the last mentioned steam supply connection, inter connections between one of the last mentioned valves and the valves controlling the gas outlet from and steam supply connec-

tion to one of said opposite generator ends, inter-connections between the remaining valves specified, so arranged that the steam supply connection to the connected ends of the generators is opened when and only when the other steam supply connection to said opposite end of each generator opens and closes as the corresponding gas outlet closes and opens, a valve controlling the gas outlet from the connected ends of the generators, and provisions operative at will to connect the valves so that the gas outlet from the connected ends of the generators closes and opens as the other gas outlets open and close.

12. Apparatus for the manufacture of water gas comprising in combination, two generators each connected at one end to the other and each having an individual 20 valved gas outlet from, and an individual valved steam supply connection to its opposite end, a valved gas outlet from, and a valved steam supply connection to the connected ends of the generators, and provisions whereby the closure of one of the two first mentioned steam supply connections while the other is open will increase the amount of steam supplied by the latter.

13. Apparatus for the manufacture of water gas comprising in combination, two generators each connected at one end to the other and each having an individual valved gas outlet from, and an individual steam supply connection to its opposite end and 35 an individual controlling valve for each of said steam supply connections, a valved gas outlet from and a valved steam supply connection to the connected ends of the generators, and a connection between the first 40 mentioned steam supply connection at the inlet sides of the controlling valves therefor, whereby the steam supplied by either of said connections is automatically increased whenever its controlling valve is 45 open and the other of said controlling valves is closed, and means for regulating the flow through said connection.

14. Apparatus for the manufacture of water gas, comprising in combination two generators each connected at one end to the other and each having an individual valved gas outlet from and an individual steam supply connection to its opposite end, a valved gas outlet from and a valved steam 55 connection to the connected ends of the generators, a cut off valve and a flow restricting device at the inlet side of said cut off valve located in each of the first mentioned steam supply connections, a conduit connecting said individual steam supply connection opening to each of the latter between the corresponding cut off valve and flow restricting device.

15. Apparatus for the manufacture of water gas, comprising in combination two

generators each connected at one end to the other and each having an individual valved gas outlet from and an individual steam supply connection to its opposite end, a valved gas outlet from and a valved steam connection to the connected ends of the generators, each of the first mentioned steam supply connections including a cut off valve and a flow restricting device at the inlet side of said cut off valve, a conduit connection between said steam supply connection opening to each of the latter between the corresponding cut off valve and flow restricting device, and an adjustable flow restricting device arranged in said connection.

16. In apparatus for the manufacture of water gas the combination of two generators each connected at one end to the other, and operating provisions including regulable means for withdrawing gas from, and supplying steam to each end of each generator whereby, while the flow through the generators may be in parallel in the blasting operation, in the gas making operation, the flow through the generators may be in series for the economical utilization of fuel in normal operation, or may be in parallel when a greater generation of gas is required, and provisions for automatically increasing the supply of steam in series operation to the end of the generator at which the gas flow begins, over that supplied to the same generator end in parallel operation.

17. In apparatus for the manufacture of water gas the combination of two generators each connected at one end to the other and operating provisions including regulable means for withdrawing the gas from, and supplying steam to each end of each generator whereby, while the flow through the generators may be in parallel in the blasting operation, in the gas making operation, the flow through the generators may be in series for the economical utilization of fuel in normal operation, or may be in parallel when a greater generation of gas is required, said means including gas and steam valves interconnected for simultaneous operation and being adapted to supply steam to the generator through which the gas flows last in series operation when the various valves are set for such operation in an amount less than that supplied to the generator when the valves are set for parallel operation.

18. Apparatus for the manufacture of water gas comprising in combination two generators each connected at one end to the other and each having an individual gas outlet from and an individual valved steam supply connection to its opposite end; and a valved gas outlet from and two valved steam supply connections to the connected

ends of the generator, one for supplying steam to the generators in parallel operation and the other of less capacity for supplying a reduced quantity of steam in series operation.

19. Apparatus for the manufacture of water gas comprising in combination two generators each connected at one end to the other and each having an individual valved gas outlet from and an individual steam supply connection to its opposite end, a valved gas outlet from, and two steam supply connections, of different capacities, to the connected ends of the generators, each of the latter being provided with and controlled by each of two valves, an individual controlling valve for each of the first mentioned steam supply connections and means interconnecting one of the last mentioned valves with a valve in each of the steam supply connections to the connected ends of the generator, means similarly inter-connecting the other valves specified, said valves and inter-connecting means being so arranged that the steam supply connection of larger capacity to the connected ends of the generators will be open when, and only when, the steam supply connections to the opposite ends of the generators are both closed and the steam supply connection of smaller capacity to the connected ends of the generators will be open when, and only when the steam supply connections to the opposite ends of the generators are one open and the other closed.

20. Apparatus for the manufacture of water gas comprising in combination two generators each connected at one end to the other and each having an individual gas outlet from and an individual steam supply connection to its opposite end, a gas outlet from and a steam supply connection to the connected ends of the generators, controlling devices for said gas outlets and steam supply connections and means operable at will which can be set in one position to insure the proper simultaneous operation in gasmaking of the various controlling devices for parallel flow in either direction through the generators according to the single generator system of working, or shifted to another position to insure the proper operation in gasmaking of the steam controlling devices for series flow in either direction through the generators when the appropriate one of the individual gas outlets above mentioned is closed and for parallel flow in one direction through the generators when both of said individual gas outlets are open, according to the modern twin generator system of working.

21. Apparatus for the manufacture of water gas comprising in combination two generators, each connected at one end to the other and each having an individual gas

outlet from and an individual steam supply connection to its opposite end and a gas outlet from and a steam supply connection to the connected ends of the generators, controlling devices for the various gas outlets and steam supply connections and a clutch which can be set in one position to insure the proper simultaneous operation in gasmaking of the said controlling devices for parallel flow in either direction through the generators according to the single generator system of working, or shifted to another position to insure the proper operation in gasmaking of the steam controlling devices for series flow in either direction through the generators when the appropriate one of the individual gas outlets above mentioned is closed and for parallel flow in one direction through the generators when both of said individual gas outlets are open, according to the modern twin generator system of working.

22. Apparatus for the manufacture of water gas comprising in combination two generators, each connected at one end to the other and each having an individual gas outlet from and an individual steam supply connection to its opposite end and a gas outlet from and a steam supply connection to the connected ends of the generators, controlling devices for the various gas outlets and steam supply connections, and a clutch adapted when in one position to interconnect the various controlling devices for simultaneous operation in gas making to effect a flow in parallel through the two generators in either direction according to the single generator system of working and shiftable to another position which insures the proper operation in gasmaking of the steam controlling devices for series flow in either direction through the generators when the appropriate one of the individual gas outlets above mentioned is closed and for parallel flow in one direction through the generators when both of said individual gas outlets are open, according to the modern twin generator system of working.

23. Apparatus for the manufacture of water gas comprising in combination two generators each connected at one end to the other and having an individual valved gas outlet from, and an individual valved steam supply connection to its opposite end, and a valved steam supply connection to and a gas outlet from the connected ends of the generators and a valve controlling the last mentioned gas outlet and adapted to open, if closed, upon a predetermined rise in pressure within the generators.

24. Apparatus for the manufacture of water gas comprising in combination two vertical generators connected together at their bottoms, regulable provisions for supplying air under pressure to the bottoms of the

generators in the blasting operation, individual valved gas outlets from, and valved steam supply connections to the tops of the generators and valved gas outlet and steam supply connections to the bottoms of said generators.

25. Apparatus for manufacture of water gas comprising in combination, two generators, each connected at one end to the other, 10 and each having an individual valved gas outlet from and an individual steam supply connection to its opposite end, a valved gas outlet from and a valved steam supply connection to the connected ends of the generators, a cut off valve in each of said indi- 15

vidual steam connections, a conduit connecting the two individual steam connections at the inlet sides of the respective cut off valves, whereby the supply of steam passing through one of said cut off valves when it is open and the other cut off valve is closed, will be increased over the amount passing through it when both cut off valves are open by steam passing through said conduit.
